LEAD-IN FILAMENT SUPPORT ASSEMBLY

Leo C. Werner, Cedar Grove, N. J., assignor to
Westinghouse Electric Corporation, East Pittsburgh, Pa., a corporation of Pennsylvania

Application December 16, 1950, Serial No. 201,183

3 Claims. (Cl. 313—272)

1

This invention relates to electron discharge devices and more particularly to lead-in filament support assembly.

In electron discharge devices, and more especially those utilizing multi-strand filaments, considerable time and money is expended in the assembly of the individual filament support rod and its cooperating parts to the center support assembly of the element mount. For example, in the pliotron type tube each of the multiple filament support rods is usually first dropped through a round clearance hole in an upper spacer disc of a center support assembly, said hole containing at its upper end a counterbored circular portion wherein is juxtaposed a metallic cylindrical washer insulated from said disc by a top ceramic washer and bottom ceramic bushing. A suitable spaced distance below said upper disc, said rod is further dropped through a similar clearance hole in a lower spacer disc of said center support assembly, said hole containing a like counterbored portion at its lower end and in said counterbored portion members as mentioned above, and then successively through an inverted open-ended metallic cup, coiled spring and a second open-ended metallic cup. While said rod is held or blocked in this position, two steel nuts, between which is gripped a copper connector strap, are screwed on the lower threaded end of said rod thereby squeezing together the spring in the desired compression and locking the copper strap in close electrical contact with the rod.

A further defect of the prior art construction is evidenced during the operation of the tube when the above mentioned parts become hot. Due to the difference of expansion in the materials used, the two nuts, which are locked to the lower screw threaded end of each filament support rod, with the connector strap gripped between their adjacent surfaces, become loose. As a consequence of this condition, a poor electrical connection, as well as an undesirable audible vibratory hum frequently results.

Hence it has been found advantageous according to this invention to overcome the high cost of the tedious assembly operation mentioned above by cutting the aforementioned clearance hole in the lower spacer disc with a radial slot extending through the periphery of said disc. The use of this slot also permits the prefabrication of the rod and strap by a brazing operation. This is accomplished by peening an eyelet in said strap to receive the end of the rod which is then brazed to the eyelet and the strap after insertion of the rod in said slot, thereby eliminating

2

an expensive threading operation of said rod and the use of the undesirable nuts, and eliminating frequently recurring loose connections of the strap.

5 In its general aspect the present invention has the objective of overcoming the difficulties and defects of the prior art filament support assembly.

Broadly, an object of the invention is to provide a construction wherein assembly of filament support rod is simplified.

Another and specific object is to provide for introducing the rod laterally into its clearance space in the lower spacer disc.

A further object is the prefabrication of the connector strap, eyelet and rod.

Another object is to provide a construction adaptable to use of brazing, rather than nut attachment, of said parts to the lower end of the filament support rod.

20 Again, an object of the invention is to obtain close electrical contact of the strap with said rod. Once again, an object is to eliminate expensive threading on the filament support rod.

Other objects of the invention will appear to those skilled in the art to which it appertains as the description proceeds, both by direct recitation thereof and by implication from the context.

Referring to the accompanying drawing, in which like numerals of reference indicate similar parts throughout the several views:

Fig. 1 is a front elevation of an electron discharge device embodying the invention;

Fig. 2 is a longitudinal section of the grid and filament mount and center support assembly;

Fig. 3 is a cross-sectional view on line III—III of Fig. 2;

Fig. 4 is a perspective view of the slotted lower spacer disc;

Fig. 5 is a detail longitudinal section of a portion of the center support assembly and filament support rod assembly;

Fig. 6 is a detail sectional view of the support rod assembly.

45 In the specific embodiment of the invention illustrated in said drawing, the reference numeral 10 designates a glass or other basal mount for the electrodes, namely anode 11, grid 12 and filaments 13 of a triode electron discharge device.

50 While a triode has been arbitrarily selected for illustrative purposes, the invention is not to be understood as restricted to employment with triodes only. The mount 10 is shown of a reentrant type, the upper outer margin being sealed to the rim of the anode 11 and the reentrant inner mar-

gin being attached to a grid-supporting flanged collar 14. Adjacent this inner margin internal sealing is effected by a cross partition glass dish 15 that the interior of the anode and basal mount may be evacuated.

The said dish 15 is first sealed to lead-in assemblies 16, evenly arranged in a sequential circular series and preferably as many in number as filament legs to the filament and coaxially to the hollow cup 22 of metallic center pedestal 20. The present showing indicates six filament legs and six of said lead-in assemblies 16.

Said lead-in assemblies 16 each consist of an outer lead 17, a hollow open-ended cup 18 to which the seal with said dish 15 is made, and lead-in fixed and rigid posts 19, all suitably brazed together in coaxial alignment. The inner ends of said post 19 are screw threaded and situated in the vicinity of but spaced from said pedestal 20. Said pedestal 20 consists of a circular plate 21 joined coaxially, as by brazing, to a hollow cup 22. The edge of said cup 22 of center pedestal 20 is in a direction away from the electrodes and in turn is sealed to a glass tubulation 23, which passes out of the reentrant part of the basal mount 10. An opening 24 in the side of the hollow cup 22 of the said pedestal 20 provides exhaust connection from the interior of the device to the tubulation 23.

Projecting inwardly from the center pedestal 20, coaxially aligned with the electrodes is metallic center support assembly 25. Said assembly 25 is shown as having an integral lower plate 27 and stud member 28 with said plate bolted to said center pedestal 20. On the top of stud 28 is a coaxial lower spacer disc 31, having a center hole therethrough of the same diameter as the inside diameter of hollow stud 28. Seated within said stud 28 and projecting upward a considerable distance from lower disc 31, is a hollow rod-like sleeve 29. A suitable distance above lower disc 31 said sleeve 29 is joined to an upper spacer disc 30 along the side walls of a center hole of said upper disc 30, thereby holding upper disc 30 and lower disc 31 in parallel spaced relation to each other and transverse to said sleeve 29. Furthermore, sleeve 29 is joined to upper disc 30 and to lower disc 31, and stud 28, as by brazing thus forming center support assembly 25. Longitudinally of and projecting from said support assembly 25, to the vicinity of the closed end of the anode, is a long coaxial rod-like center support 32. Said support 32 is shown as having a threaded connection with bottom plate 27.

The upper spacer disc 30 has holes 33 therethrough in corresponding number and same circular sequence as the lead-in posts 19 but shown somewhat closer to the axis than said posts 19. The upper end of the holes 33 in said disc 30 have a counterbored portion 34 so as to receive and retain in the order named ceramic bushing 35, metallic guide washer 36, and ceramic washer 37, thereby insulating guide washer 36 from said upper disc 30. Displacement of said washers 36 and 37 and bushing 35 in a direction toward the anode end is prevented by metallic washer-like securing ring 38 situated flatwise and coaxially upon upper spacer disc 30 and spot welded or otherwise secured thereto. The guide washers 36 each have a center hole to admit passage of filament support rods 39 therethrough. Corresponding but larger holes are provided in a circular series in securing ring 38, for passage of said rods 39 without contact between said rods 39 and said securing ring.

The lower spacer disc 31, preferably symmetrical in shape to upper spacer disc 30, has holes 40 and radially directed slots 41 therefrom to the periphery of the disc in corresponding number and the same circular sequence as the lead-in posts 19. Said slots 41 as shown have a width substantially the same as the diameter of the holes 40 in the lower spacer disc 31, and the said holes are each in vertical alignment with a corresponding hole 33 of upper spacer disc 30. Thus filament support rods 39 are parallel to center support 32 when positioned coaxially through aligned holes 33 and 40 of the upper and lower spacer discs 30 and 31; said holes 40 of the lower spacer disc 31 have a counterbored portion 42 next the bottom of disc 31, said counterbored portion 42 having the same diameter and depth as the counterbored portion 34 of the holes 33 through upper disc 30.

The filament support rods 39 are quite long so as to situate their lower ends remote from the filament and subject to as little of the heat from the filament as possible. The said lower end of each rod 39 has attached thereto a flexible U-shaped connector strap 43, preferably copper, held securely between the head flange and peened flange of a metallic eyelet 44. The other end of strap 43 is secured between two suitable nuts to the threaded end of the next adjacent lead-in post 19 which is at a position accessible to enable the nuts to be securely tightened. The straps 43 are unified with support rods 39 by brazing the eyelets, suitably with .010" silver solder, to the lower ends of said rods, thereby forming filament support rod assembly 45. Furthermore, above eyelet 44 on each rod 39 is provided a spiral spring 46 under compression. That these springs 46 may better withstand operating temperatures it is preferable that they be made of tungsten wire. As shown, each end of each spring 46 is confined by a metallic cup 47, individual to the respective end of the spring 46 on which applied.

The upper surface of the top cup 47 in each case rests against ceramic washers 37 on rod 39 contained in counterbored portion 42 of the hole 40. To prevent contact between disc 31 and cup 47, the outside diameter of cup 47 is less than the diameter of the counterbored portion 42. Also on rod 39 and contained within said counterbored portion 42 abutting the upper surface of washer 37 are guide washer 36 and a ceramic bushing 35.

The filament support rods 39 as mentioned above are quite long and extend a considerable distance above upper spacer disc 30 and securing ring 38. The upper end of each rod 39 has a foot end of a leg of filament 13 secured thereto, as by arc welding. The end portions of the several filament legs are spaced by a common metallic or other plate 48 carried by the upper center support 32 and are disposed radially across the plate 48 and longitudinally of the said support 32 to which they are appropriately welded or otherwise secured. Positive and negative sides of power supply are suitably applied to the filaments, and accomplished for instance by connecting the positive and negative supply to alternate filament legs through the lead-in posts 19, connector straps 43 and rods 39, in which arrangement center support 32 is electrically neutral.

According to our invention, each filament support rod assembly 45 consisting of filament support rod 39, eyelet 44 and connector strap

43, is made up prior to the operation of mounting the element assembly. The shank of eyelet 44 is inserted through the strap 43 and then peened over against said strap thereby immovably securing said eyelet to the strap. The eyelet 44 and strap 43 sub-assembly is then brazed suitably flush to the lower end of rod 39 with silver solder, thereby forming filament support rod assembly 45.

Coiled spring 46 and containing cups 47, their open ends facing each other, ceramic washer 37, guide washer 36 and ceramic bushing 35 are introduced, in the order named, over the top end of filament support rod 39 downwardly into position on said rod to its lower end against the top surface of eyelet 44. The upper end of each rod 39 is pushed obliquely upward through hole 33 inclusive of its counterbored portion 34 of upper disc 30 and toward center support 32 until said upper end reaches approximately its assembled height above the upper spacer disc. Compressing the above mentioned parts on the lower end of rod 39 sufficiently, as by the fingers of a hand, so that the upper surface of ceramic bushing 35 will clear the lower edge of lower spacer disc 31, said rod 39 is pushed laterally toward center support 32 through radial slot 41 of lower spacer disc 31 until said rod reaches its coaxial position in hole 40. Releasing the compression on the above mentioned parts assembled on the lower end of said rod 39 and at the same time blocking said lower end with a suitable temporary stop 49, metal or otherwise, ceramic bushing 35, guide washer 36, and ceramic washer 37 are seated, in the order named, in the counterbored portion 42 of radial slot 40, thereby locking said rod 39 in a position parallel to center support 32. The stop 49, as shown in Fig. 5, rests on circular plate 21 of center support assembly 25 and on the head of a bolt which joins said plate and plate 21 of the center pedestal 20. An additional one each of ceramic washer 37, guide washer 36, and ceramic bushing 35 are then applied over the upper end of and around said rod 39, downward into the counterbored portion 34 of hole 33 in upper disc 30.

When the remaining filament support rods 39, five as indicated in this showing, are similarly assembled with their applied parts as above described and shown in Fig. 6, they are also applied in place upon the center support assembly 25. Securing ring 38 is applied over the upper ends of and around center support 32 and adjacent filament support rods 39, onto the top surface of upper spacer disc 30 and joined thereto, as by welding. After arc welding the foot end of each leg of filament 13 to the upper end of the corresponding filament support rods 39 and disposing the end portion of said filament radially across common plate 48 and longitudinally of center support 32, the blocking means 49 at the lower ends of said rods 39 is removed.

Thus it will be seen from the foregoing description that my invention has overcome the defects and difficulties of the prior art filament support assembly. By providing radial slots 41 in conjunction with clearance holes in lower spacer disc 31 for each filament support rod 39 the assembly of the filament support rods and their cooperating parts to the center support assembly 25 of the element mount has been simplified. The prefabrication of each connector strap 43 and eyelet 44 as by peening said eyelet 44 and the subsequent brazing of said parts with silver solder to the lower end of said rod 39 to

lock said strap 43 in close electrical contact with said rod 39, eliminating an expensive thread on the lower end of said rod 39, further simplifies the filament support rod assembly 45, and eliminates the prior art defect of poor electrical connection and resulting hum during the operation of the tube.

Although the preferred embodiment of my invention has been disclosed, it will be understood that modifications may be made within the spirit and scope of the appended claims.

I claim:

1. An electron discharge device having a basal end and a hollow anode remote from and opening toward said basal end, a filament within said anode having a plurality of legs with foot ends therein, rods interposed between the foot ends of said filament legs and said basal end and each connected to a leg of the filament, said rods each having at the basal end a connector and eyelet peened together and brazed to said basal end of said rod, a spacer interposed between said rods near the basal ends thereof, said spacer having holes and radial slots therein, said slots extending from said holes to the periphery of said spacer, said holes each having a counterbored portion on the underside, an insulating washer, guide washer and insulating bushing on said rod and in said counterbored portion, a spring on said rod and under compression between said bushing and said eyelet, a second spacer interposed between said rods near said anode ends thereof, said spacer having a hole with a counterbored portion next the upper end thereof around and of greater diameter than said rod, an insulating bushing, guide washer and insulating washer in said counterbored portion and around said rod, and means at the end of said counterbored portion for retaining said washers and bushing therein.

2. An electron discharge device having a basal end and a hollow anode remote from and opening toward said basal end, a filament within said anode having a plurality of legs with foot ends therein, rods interposed between the foot ends of said filament legs and said basal end and each connected to a leg of the filament, said rods each having at the basal end a connector and eyelet put together and joined to said basal end of said rod, a spacer interposed between said rods near the basal ends thereof, said spacer having holes and radial slots therein, said slots extending from said holes to the periphery of said spacer, said holes each having a counterbored portion on the underside, an insulating washer, guide washer and insulating bushing on said rod and in said counterbored portion, a spring on said rod and under compression between said bushing and said eyelet, a second spacer interposed between said rods near said anode ends thereof, said spacer having a hole with a counterbored portion next the upper end thereof around and of greater diameter than said rod, an insulating bushing, guide washer and insulating washer in said counterbored portion and around said rod, and means at the end of said counterbored portion for retaining said washers and bushing therein.

3. An electron discharge device having a basal end and a hollow anode remote from and opening toward said basal end, a filament within said anode having a plurality of legs with foot ends therein, rods interposed between the foot ends of said filament legs and said basal end and each connected to a leg of the filament, said rods each

having at the basal end a connector and eyelet put together and joined to said basal end of said rod, a spacer interposed between said rods near the basal ends thereof, said spacer having means for the lateral insertion of said rods therein, a second spacer interposed between said rods near said anode ends thereof, said spacer having a hole with a counterbored portion next the upper end thereof around and of greater diameter than said rod, an insulating bushing, guide washer 10 and insulating washer in said counterbored portion and around said rod, and means at the end of said counterbored portion for retaining said washers and bushing therein.

5 LEO C. WERNER. 15
